(57) **CLAIM**

The ornamental design for a mobile phone with graphical user interface, as shown and described.

DESCRIPTION

FIG. 1 is a front view of a first embodiment of a mobile phone with graphical user interface showing our new design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a sixth embodiment thereof; FIG. 7 is a front view of a seventh embodiment thereof; FIG. 8 is a front view of an eighth embodiment thereof; FIG. 9 is a front view of a ninth embodiment thereof; and FIG. 10 is a front view of a tenth embodiment thereof. The cellphone shown in broken lines depict the environment where a graphical user interface is embodied that forms no part of the claimed design.

1 Claim, 10 Drawing Sheets
